UNITED STATES PATENT OFFICE.

ALFRED L. BOEGEHOOLD, OF DAYTON, OHIO, ASSIGNOR TO GENERAL MOTORS RESEARCH CORPORATION, OF DAYTON, OHIO, A CORPORATION OF DELAWARE.

INTERNAL-COMBUSTION-ENGINE CYLINDER AND PROCESS OF MAKING SAME.

Application filed December 14, 1922. Serial No. 606,797.

The present invention relates to air cooled cylinders for internal combustion engines, and the principal object thereof is to provide an improved cylinder wherein the joint or union between the cylinder wall and the usual heat radiating fins thereupon is of such a character as to provide for a more effective and efficient flow of heat from the cylinder wall to the fins, and to the surrounding atmosphere, than has commonly heretofore been attained.

Further objects and advantages of the present invention will be apparent from the following description, reference being had to the accompanying drawings, wherein a preferred form of embodiment of the present invention is clearly shown.

In the drawings:

Fig. 1 illustrates partly in vertical section a cylinder made in accordance with my invention.

Fig. 2 is a vertical section through a mold used in producing my improved cylinder and having a cylinder barrel and prepared fins set therein.

Fig. 3 is a horizontal section of Fig. 2, on line 3—3.

Fig. 4 is an enlargement of a portion of Fig. 3.

The preferred materials used in making the present type of cylinder are those mentioned in the specific description immediately following but it should be understood that other materials may be used provided they are suitable and have properties adapting them for the functions which they will have in the finished cylinder.

The cylinder shown in Fig. 1 preferably consists of a steel barrel 10 having a cast on iron base 11. It also shows a bi-metallic head consisting of a cast in plate of iron 12 and a cast on plate or equalizer 13 of copper, these being the preferred metals used for such parts or portions.

Surrounding the upper portion of barrel 10 is a set of cooling fins 14 which will be more particularly described later. And between these fins 14 and barrel 10 is a thin layer of copper 15.

The bonds between the several portions are permanent metallic bonds and are efficiently heat conductive, which property is highly desirable at the junction between the

fin material and the cylinder barrel and head and between the head materials and 55 between these latter and the barrel.

In making my improved cylinder, a steel tube is set in a suitable mold and an iron plate of suitable thickness cast in one end thereof in any well known manner so as to 60 produce a welded junction between the two metals. Such a prepared tube is indicated at 10 and 12 in Fig. 2.

A suitable mold is then prepared, as indicated in Figs. 2 and 3, having embedded 65 in its walls a set of cooling fins 14 with their bases projecting into or forming a wall of the mold proper. The mold proper should be of sufficient size to allow the tube 10 to be positioned therein with a small annular space between the tube and the walls of the mold as indicated at 20 in Figs. 2 and 4. The tin plated tube 10 is then properly positioned in the mold with a space 70 21 beneath it for the molding of the head portion 13.

Around the upper end of the tube there is also formed a second mold 30 for casting base 11.

There are provided also a gate 35 and 80 riser 36 for the lower mold and a gate 37 and riser 38 for the upper mold.

When the molds have been thus prepared with the fins 14 and tube 10 in place, a thin cup of baked core material 40 is placed inside of tube 10 and after runner boxes have been placed thereon as indicated, the mold is ready for pouring.

The pouring operation is conducted as follows: First molten iron is poured into 90 cup 40 for the purpose of highly heating tube 10 and head portion 12. Then after an interval of a few seconds, to give the tube a chance to get hot, iron for the base 11 is poured in through gate 37 and, immediately thereafter, copper is poured through gate 35.

The tube being thoroughly and highly heated, the copper runs in readily and fills space 21 and rises in annular space 20 welding itself to plate 12, fins 14 and tube 10 forming a permanent and effective heat conductive bond. The copper which rises in the annular space 20 provides the thin layer of copper 15 of the finished cylinder, 105 as will be appreciated.

The cylinder is then removed from the mold cleaned and finished.

While the forms of embodiment of the invention as herein shown and described, constitute preferred forms, it is to be understood that other forms might be adopted, all coming within the scope of the claims which follow.

What I claim is as follows:

- 10 1. An internal combustion engine cylinder comprising a thin steel barrel closed at one end, cooling fins extending longitudinally of the said barrel and radially therefrom, and a metallic jacket supplied to said cylinder in a molten condition and filling a space initially present between the exterior of said barrel and the inner ends of said fins.
- 15 2. An internal combustion engine cylinder comprising a thin steel barrel closed at one end by a plate, cooling fins extending longitudinally of said barrel and radially therefrom, and a metallic jacket supplied to said cylinder in a molten condition and enclosing said plate and filling a space ini-

tially present between the exterior of said barrel and the inner ends of said fins.

3. An internal combustion engine cylinder comprising a thin steel barrel closed at one end by a plate, copper cooling fins extending longitudinally of said barrel and radially therefrom, and a copper jacket the material of which is supplied to said cylinder in a molten condition and which material fills a space initially present between the exterior of said barrel and the inner ends of said fins.

4. An internal combustion engine cylinder comprising a thin steel barrel closed at one end by a plate, copper cooling fins extending longitudinally of said barrel and radially therefrom, and a copper jacket the material of which is supplied to said cylinder in a molten condition and which material encloses said plate and fills a space initially present between the exterior of said barrel and the inner ends of said fins.

In testimony whereof I hereunto affix my signature.

ALFRED L. BOEGEHOOLD.
